BASEBALL BAT

Fred E. Robarge, Chicopee Falls, Mass.

Application September 19, 1938, Serial No. 230,681

2 Claims. (Cl. 273—72)

My invention relates to improvements in baseball bats and has as one of the principal objects thereof the provision of a baseball bat equipped with means to improve the strength, efficiency and reliability thereof without change in the usual normal overall dimensions of said bat.

Another object of my invention is to provide a bat of the character described which is simple in construction, durable in use, and economical in manufacture.

Other objects and advantages will be apparent from the following description, appended claims and annexed drawing.

Referring to the drawing wherein like reference characters designate like parts throughout the several views:

Figure 1 is a side elevation of a baseball bat constructed in accordance with my invention.

Figure 2 is an enlarged detail sectional view taken on the line 2—2 of Figure 1.

Figure 3 is a detail sectional view taken on the line 3—3 of Figure 2.

My baseball bat comprises an elongated body portion 5 fashioned with a pair of connected batting and handle sections 6 and 7 respectively. The sections 6 and 7, adjacent their abutting ends, are recessed on their respective peripheries to accommodate a metal tube or sleeve 8 in flushed relation therewith, said tube 8 serving as a reenforcement between the handle and batting sections of the bat. The abutting face of the section 6 is formed with a tapered recess 9 and the adjacent face of the section 7 is fashioned with a tapered projection 10 seated within said recess 9 whereby to effect alignment of said sections when assembled.

The end of the section 6, adjacent the section 7, is formed with a centrally disposed cul-de-sac or socket 11 registering with a centrally disposed opening 12 extending through the handle section. A dowel member 13 is located within said socket 11 and opening 12 and maintained therein by glue or the like for fixing the sections together.

In assembling the parts, the abutting ends of said sections are inserted in respective ends of the tube 8 and aligned therein and in abutting relation by the projection 10 seating within the recess 9. The dowel member is then inserted through the opening 12 into the socket 11 to secure said sections fixed together within the tube. The tube 8 materially strengthens the bat and minimizes the breaking thereof due to contact with a swiftly pitched ball.

The added weight of the reenforcing member 8 serves as a balance for the bat and precludes the handle section breaking from the batting section thereof and thereby assists a player in maintaining his batting average which would be lowered should the bat break.

It is to be distinctly understood that various changes and modifications may be resorted to in the construction and arrangement of the parts without departing from the spirit of the invention or scope of the appended claims.

What I claim is:

1. A baseball bat comprising a body having attached batting and handle sections formed with abutting end portions, one of said portions fashioned with an axially extending socket having an end wall and the other of said portions provided with a dowel member extending into said socket and effecting alignment of said sections, and a reenforcing member surrounding said portions and extending beyond the end wall of said socket and reenforcing said portions.

2. A baseball bat comprising a body formed with connected batting and handle sections, a dowel member extending through said handle section and having an end portion disposed within said batting section to maintain said sections in connected condition, and a reenforcing member surrounding said sections and extending beyond said end portion of said dowel member within said batting section.

FRED E. ROBARGE.
